UNITED STATES PATENT OFFICE.

CHARLES C. RICHMOND, OF BOSTON, MASSACHUSETTS.

LAMP-BURNER.

SPECIFICATION forming part of Letters Patent No. 257,614, dated May 9, 1882.

Application filed March 13, 1882. (No model.)

To all whom it may concern:

Be it known that I, CHARLES C. RICHMOND, of Boston, in the county of Suffolk and State of Massachusetts, have invented an Improvement in Lamp-Burners, of which the following is a full, clear, and exact description, reference being had to the accompanying drawings, making part of this specification, in which—

Figure 1 is a perspective view of a burner constructed in accordance with my invention and applied to a lamp designed for use in a lantern. Fig. 2 is a vertical section through the center of the same.

My present invention has particular reference to that class of burners for lamps used independently or in connection with lanterns in which chimneys are dispensed with; and my said invention consists in the combination of two features—viz., a perforated cap surrounding the wick-tube and an inverted perforated bell-shaped casing outside of the cap, the base of said cap being secured directly to the base of the casing, said arrangement preventing the extinction of the light incident to the usual construction of burners when moved in various directions from place to place.

To enable others skilled in the art to understand and use my invention, I will proceed to describe the manner in which I have carried it out.

In the said drawings, A represents a lamp-burner having an ordinary wick-tube, *a*, with a collar, *b*, surrounding it, located near its top, and of such size and shape as to form spaces *c* between it and the opposite sides of the wick-tube for the passage of air-currents upward to feed the flame of the lighted wick. Outside the wick-tube is a slotted or perforated cap, *d*, and outside the cap an inverted perforated bell-shaped casing, *e*, the base of the cap resting on and being preferably secured to the base of the casing, the latter being provided with an interior screw-thread or other means of fastening it to the central portion, *f*, of the burner, the lower end of which is provided with the usual thread to admit of its being screwed into the collar *h* at the top of the lamp B.

A lamp-burner having my two features—viz., the inverted perforated bell-shaped casing and the perforated cap, combined and arranged

in the manner above described—possesses the following advantages: When the lamp (whether used independently of or in connection with a lantern-case, and without a chimney) is raised in carrying it the column of air against which it is brought into contact is divided into a series of currents, some only of which are free to pass through the perforations in the inverted bell-shaped casing, said portion only passing through the slots or perforations in the cap and supplying just sufficient air to maintain the combustion, whereas were a closed casing employed instead the greater portion of the column of air would not have an opportunity of flowing off or of being dissipated outwardly at the instant of raising, but would all impinge and concentrate upon the flame, and consequently extinguish it, being driven through the perforated cap *d* directly thereon. Again, when a burner having my invention applied thereto is lowered the column of air disturbed thereby is also subdivided into many currents, some of which, sufficient to maintain combustion, are free to pass upward through the perforations in the casing and through the perforations in the cap to the flame, whereas were an ordinary closed casing and closed cap employed the air displaced by the lowering of the lamp would be diverted or thrown off outside the periphery of the casing, resulting in a temporary vacuum, in which the flame would be extinguished, as oxygen is essential to combustion.

Another advantage resulting from the application of my invention is that the expense of chimneys and the inconvenience of adjusting them on or of removing them from the burners is avoided.

I am not aware that a chimney has heretofore been dispensed with where a perforated inverted bell-shaped casing, either with or without a perforated cap, *d*, is employed. By securing the base of the perforated cap to the perforated inverted casing and providing the inside of the latter with a screw-thread or other suitable fastening, both casing and cap may be removed at one operation.

I am aware that a perforated cap has been employed in connection with a perforated casing; but in this case a series of supports are interposed between the cap and the casing,

these supports elevating the cap a considerable distance above the latter, the burner thus constructed being provided with a chimney-band to enable a chimney to be used therewith.

5 What I claim as my invention, and desire to secure by Letters Patent, is—

An inverted perforated bell-shaped casing, *e*, in combination with and located outside of a perforated cap, *d*, the base of said cap being

secured directly to the bottom of said casing, to as and for the purpose described.

Witness my hand this 10th day of March, 1882.

CHARLES C. RICHMOND.

In presence of—

N. W. STEARNS,
THOMAS W. FARNSWORTH.
